SUPPORT AND SPACER FOR CONCRETE
REINFORCEMENTJohn L. Callaway, Jr., Birmingham, Ala., assignor
to Connors Steel Company, a corporation of
Delaware

Application February 5, 1940, Serial No. 317,339

3 Claims. (Cl. 72—122)

My invention relates to a support and spacer for concrete reinforcement designed both properly to support and space reinforcing bars assembled at different levels in a form for pouring a concrete slab, beam, footing, or the like.

More particularly, my invention contemplates an extremely simple construction in which bars are welded together to form X-shaped stands which are rigidly connected by a horizontal tie bar disposed at the predetermined level required for supporting the lower course of reinforcing bars, a temperature or support bar being cradled in the top crotch of the X-stands at the predetermined level for the support of the upper course of reinforcing bars. Preferably the X-stands are assembled on centers corresponding to the spacing of the bars in the upper course so that they may also serve the function of correctly spacing these upper bars. The lower tie bar may carry foot supports intermediate the X-stands, which may serve to correctly space the lower course of bars and, if desired, to secure them fast in staggered relationship to the upper bars.

My structure requires merely the simplest form of welding to produce the stand bar assembly and the stands have the special advantage of correctly placing the temperature or upper support bars in the slab and of supporting on them the upper course of reinforcing bars.

My invention further comprises the novel details of construction and arrangement of parts which, in their preferred embodiments only, are illustrated in the accompanying drawing, in which:

Fig. 1 is a perspective view of the reinforcement assembly for a concrete slab, showing one of my improved support and spacer elements interposed where the bars are disposed at different levels.

Fig. 2 is a similar perspective view enlarged and broken away of my support and spacer assembly unit.

Fig. 3 is a front elevation enlarged of my support and assembly unit with its supplemental legs and stands modified to permit tying reinforcing bars in position on the support when such is required.

Similar reference numerals refer to similar parts throughout the drawing.

In the embodiment of my invention, I show my improved support and spacer units for concrete reinforcement as comprising a series of X-stands formed by the members 5 and 6 which are crossed near their upper ends and there welded at 7. The legs 6 are cross connected, at a

predetermined elevation above the base level of the stands, by means of the tie bar 8 which is welded, or otherwise made fast, to each leg 6 so as to assemble the stands in rigid relationship for transport and use on the job.

The stand elements 5, 6 and 8 can be of rods or wire of suitable gauge and if the stands are spaced widely enough to require an intermediate support for the tie bar 8, short supplemental legs 9 can be welded to the tie bar 8 between the X-stands and disposed preferably with the legs 6. These supplemental legs 9, as shown in Fig. 2, project far enough above the bar 8 to serve as a means for centering or spacing the lower reinforcing bars 10 and, if desired, as shown in Fig. 3, their upper ends may extend far enough above the bar 8 to form tie members 11 by bending them over the bars 10 to secure them in position where such is required. The ordinary temperature bar, or equivalent support element, 12 is placed loosely in the top crotches formed by the X-stands and does not need to be made fast thereto, thus leaving it to be placed in position only after the bars 10 of the lower course are in place. This leaves free the selection of the elements 12 to suit the job since they are not integral with the support.

It is contemplated that the reinforcing bars 13, forming the upper course of reinforcement, will be positioned against or alongside the X-stands, and if desired, as shown in Fig. 3, one of the stand leg elements 5 or 6 can be sufficiently elongated to provide a tie end 14 which is adapted to be bent over to tie or secure the adjacent upper bar 13 in place.

The manner of use of my invention will be readily understood, the X-support and spacer units being set in parallel relationship normal to the reinforcing bars they support; the lower bars 10 are then placed on the supporting elements 8 and they can be tied in place thereon if desired; the temperature or support bars 12 are then dropped in aligning top crotches of the X-stands; and the upper reinforcing bars 13 are then set in place on the bars 12, alongside the X-stands if desired and tied in position in the manner described or otherwise.

In Fig. 1 the bars 13 of the upper course are shown bent down to the level of the lower bars 10 throughout the intermediate portion of the slab and throughout this portion both bars can be satisfactorily supported by the single level spacer element 15, which forms no part of my present invention.

My improved unit assembly is very light, strong

and quite adequate for its purposes, and offers no interference to the convenient placing of the several courses of reinforcement of the slab, nor to the flow of the concrete.

While I have shown my invention in but two forms, it will be obvious to those skilled in the art that it is not so limited, but is susceptible of various other changes and modifications, without departing from the spirit thereof, and I desire, therefore, that only such limitations shall be placed thereupon as are imposed by the prior art or as are specifically set forth in the appended claims.

What I claim is:

1. A supporting and spacing element for concrete reinforcement, comprising a plurality of substantially X-shaped stands formed of a pair of support members secured together near the crotch of the X-shape and arranged in spaced parallel relation, and a longitudinal tie bar rigidly connected to the corresponding leg of a plurality of said stands and disposed at an inter- 15

mediate level between the base and the level of the top crotch of said stands, said top crotches of the stands being disposed in alignment and adapted to receive and support a demountable

5 bar for supporting an upper course of reinforcement and the said tie bar being adapted to support a lower course of reinforcement, whereby said elements are adapted to support an assembly of reinforcing bars lying in different levels.

10 2. A supporting and spacing element for concrete reinforcement according to claim 1, in which the X-stands are formed by straight rods intersecting at an angle near their upper ends and there welded together.

20 3. A supporting and spacing element for concrete reinforcement according to claim 1, in which the tie rod has rigidly attached thereto, between said X-stands, supplemental supporting legs which extend far enough above said rod to be bent over and tie juxtaposed reinforcing rods in fixed position on said tie rod.
